UNITED STATES PATENT OFFICE.

IGNACIO LÁZAGA, OF SALEM, VIRGINIA.

MACHINE FOR PACKAGING ARTICLES.

Application filed October 29, 1921. Serial No. 511,343.

This invention relates to a machine for packaging articles, such, for instance, as cigarettes.

The object of the invention is to provide a single machine which will rapidly and efficiently count off the articles to be packaged, compress them compactly, feed them into the path of the wrapper which has been printed, and wrap and fold the printed 10 wrapper around the articles, and finally paste the wrapper preparatory to the delivery of the package from the machine.

In the accompanying drawings:

Fig. 1 is a side elevation of the entire 15 machine;

Fig. 2 is a top plan view thereof;

Fig. 3 is an end view;

Fig. 4 is an end view looking in the opposite direction to that of Fig. 3;

Fig. 5 is a skeleton perspective view of the transfer-wheel and its associated plungers and mechanism for operating the same;

Fig. 6 is an enlarged side elevation of the wrapper feeder mechanism;

Fig. 7 is a detail view of the feed-roller and associated parts;

Fig. 8 is a front view of the wrapper feeding mechanism;

Fig. 9 is a side elevation taken in the 20 opposite direction from Fig. 6;

Fig. 10 is a detail view of the paste-applying mechanism;

Fig. 11 is a side view thereof;

Fig. 12 is a side view looking in the opposite direction from Fig. 11;

Fig. 13 is a plan view of the endless delivery mechanism;

Fig. 14 is a side elevation thereof;

Fig. 15 is a transverse section on line 25 15—15 of Fig. 13;

Fig. 16 is a perspective view showing the relative position of the wrapper and the plunger which is adapted to force the charge into the wrapper;

Fig. 17 is a view similar to Fig. 16, showing a different step in the operation;

Fig. 18 is a similar view showing still another step in the operation;

Fig. 19 is a view showing the first step 30 in the folding operation;

Fig. 20 is a similar perspective view showing the method and time at which the paste is applied;

Fig. 21 is a view showing the second folding operation.

Fig. 22 is a vertical sectional view through the transfer wheel;

Fig. 23 is an enlarged transverse sectional view through one of the pockets of the transfer wheel;

60

Fig. 24 is a detailed plan view of the discharge plunger;

Fig. 25 is a side elevation thereof;

Fig. 26 is an end view of the plunger;

Fig. 27 is an enlarged transverse section 65 through the pastebox;

Fig. 28 is a plan view thereof;

Fig. 29 is a transverse section through the pastebox;

Fig. 30 is a horizontal section through 70 one end of the mechanism for moving the cigarettes against the wrapper.

The numeral 1 indicates the main frame of the machine, comprising a table 2 and an intermediate structure 3 arranged below the table.

75

Arranged beneath the table is a main drive-shaft 4 having secured to the outer end thereof a drive-pulley 5 and loose pulley 6. The main drive-shaft 4, through gears 7 and 8, drives a transverse counter-shaft 9, and through the gears (11 and 11') a longitudinal counter-shaft 12 is driven as shown in Fig. 5.

Arranged above the table is a cigarette hopper 13, the base 14 of which is mounted upon an L-shaped bracket 15 pivoted as at 80 16 upon the intermediate structure, the laterally-extending arm 17 of the bracket adapted to be actuated by the cam 18 secured to the longitudinal countershaft 12, 85 the arrangement serving to agitate the hopper. The base portion 14 of the hopper is preferably provided with a plurality of vertically arranged partitions 19 forming compartments whereby the cigarettes are stacked 90 in vertical rows.

The numeral 20 indicates a rotary transfer wheel arranged to turn in a direction transversely of the machine, being mounted upon the longitudinally-arranged shaft 21

100

journaled in suitable bearings 22 upon the table of the machine. This transfer wheel 20 is given a step by step rotation by means of the well-known Geneva gear construction, consisting of the gear 23 keyed to shaft 25' and gear 23' keyed to the shaft 28. The shaft 25' is connected with the shaft 21 by means of the sprocket-wheel 24 keyed to shaft 21 and gear 25 keyed to shaft 25' and sprocket-chain 26, the gear 23' deriving its 105 110

power from the jack-shaft 28 which in turn is provided with a sprocket-wheel 29, over which passes a sprocket-chain 30, which in turn passes over a sprocket-wheel 31 keyed to the longitudinal countershaft 12. This transfer wheel 20 is placed directly in the rear and in alignment with the base 14 of the hopper 13, said wheel preferably being provided with a plurality of radially-arranged rectangular pockets 32 of such dimensions as to receive each a predetermined number of cigarettes from the hopper.

As a means for transferring the cigarettes from the hopper to the pockets of the wheel, I preferably provide a horizontally reciprocating plunger 33, the forward end of which is slotted to form a plurality of projections of such dimensions as to pass through the vertically-arranged channels in the base of the hopper.

This plunger is adapted to force a predetermined number of cigarettes from the hopper to a pocket of the wheel. This plunger is pivotally secured to a reciprocating carriage 34, which is adapted to travel upon horizontal ways 35, the carriage being actuated by a rock-arm 36 pivoted at its lower end to the machine, the upper end thereof being pivotally connected as at 36' to the carriage 34. The rocker-arm 36 is preferably actuated by crank 37 keyed to the jack-shaft 9, the crank being provided with pin 38 adapted to be received in a slot 39 in the rocker-arm 36 as shown in Fig. 5. This arrangement imparts a reciprocating movement to the plunger 33.

As stated, the transfer-wheel is rotated, step by step, to pass the face of the hopper to receive in its respective pockets the charge of cigarettes, they being transferred in turn to the opposite side of the machine, where they are to be suitably wrapped.

It is desirable, however, to compress the charge more compactly before being wrapped, and for this purpose (as best shown in Figs. 22 and 23) I preferably provide the several pockets 32 with radially-arranged plungers 40, the inner end of each being adapted to bridge the hub 41 of the wheel 20 being provided with a set of rollers 42, which are received in annular grooves 43, 43, arranged eccentrically of the transfer-wheel in such a manner as to impart a radial movement to the plunger as the wheel is rotated, thereby compressing the contents of the pockets as they reach the opposite side of the machine.

The cigarettes having been placed in the front of the opening for the folding device, the mechanism for feeding the wrapper into position to be applied will now be described. Directly above the folding device, there is placed a wrapper-container and feeder 44. The pile of wrappers is indicated by the numeral 45, as best shown in Fig. 6. The

bottom of the receptacle 44 has projecting through it a feed-roller 46, and above it is a gravity-acting stop 47 carried by a pivoted yoke 48 against which the wrappers rest. The feed-roller 46 has affixed to it a suitable gear 49 both of which are keyed to the shaft 49' the gear 49 being driven from a segmental gear 51 fast on the gear 52 driven from the gear 53 arranged on a stub-shaft 54, which, in turn, is driven by gear 55 carried by the stub-shaft 56, upon which is mounted a bevel-gear 57 meshing with a suitable bevel gear 58 driven by a substantially vertically-arranged auxiliary drive-shaft 59, deriving its power from the countershaft 9 by means of the bevel-gears 60 and 61.

From this construction, it follows that while gear 51 constantly rotates, it rotates the gear 49 and its feed-roller 46 for a half revolution, and then said roller is at rest until the gear 51 rotates during the other half of the revolution. Therefore, the feed-roller feeds a wrapper during one period, and then rests for a like period, before feeding the next wrapper. In order to insure a proper feed of the wrappers, a rotatable jogger 62 is arranged so that as it rotates it passes upward against the bottom of the lowest wrapper and jogs it until its front end projects between the feed-roller 46 and the gravity stop 47, so that the feed of the wrapper will be insured.

The jogger 62 is driven by sprocket-chain 63, passing over sprocket wheel 63' keyed to the shaft 62' upon which the jogger 62 is keyed. The sprocket-chain 63 derives its power from the shaft 49' to which is keyed the sprocket wheel 50' over which the sprocket chain passes as shown in Fig. 9. The wrapper after it is fed by the roller 46 is projecting between the two rolls 64 and 65, the first of which is affixed to and driven by a shaft 66 to which is secured a spur-gear 67 adapted to mesh with the spur-gear 52. From said feed-roll, the wrapper falls downwardly by gravity through a chute 68 until it rests upon the fixed stub or support 69, in such a position as to receive the charge about to be ejected from the pocket of the transfer-wheel, which is now aligned with the opening of the folding device.

With the wrapper in this position, it is ready to have the charge of cigarettes shoved forward against the wrapper to be wrapped therein. This action is accomplished by means of longitudinal movable plates 70 operated from a cross-head 71, which latter and the plates 70 are given an extended backward and forward movement by means of a rocker-arm 73, the upper end of which is secured to the bottom of the cross-head 71, the lower end of which rocker-arm is pivotally supported as at 75

(see Fig. 5). This rocker-arm 71 is given a movement by means of a crank-arm 76 carried by the crank-shaft 9 before described, said crank-arm having its wrist-pin movable 5 in a slot 77 in said rock-arm 73.

It follows from this construction that during one part of the operation, the rock-arm 73 with its cross-head 71 and the plates 70 are moved longitudinally forward to 10 move said plates and the charge of cigarettes against the wrapper, as will be shortly described. I have referred to the plates 70 between which the charge of cigarettes is located. The object of these plates is to 15 take all of the strain off the cigarettes, and hence avoid the possible buckling of the latter when together with the wrapper they are pushed forward into folding mechanism.

The construction by which the plates are 20 operated will now be described. As shown in Figs. 24 and 25, there are two fixed parts 80 and 81 of the frame, each having rubber 25 cushions 82. The aforesaid cross-head 71 slides with respect to the two frame members 80 and 81, and has connected to it (so as to travel with it) two blocks 83, each of 30 which has a pin 84 extending toward each other, as illustrated in Fig. 24. Said cross-head 71 also has connected to, and movable 35 with it two longitudinal bars 85, the outer ends of which are connected to a cross-head 86. Straddling the ends of the bars 85 are the plates 70 before-mentioned, which are 40 movable with respect thereto, said plates being secured to a block 87, and the latter being connected to one end of an extension-bar 88, the other end of which is rigidly connected to a friction-bar 89 arranged above the bar 88 and extends inwardly above the block 71.

Each end of the friction-bar 89 has a 45 bumper 90 in line with one of the cushions 82, and the inner end of the friction bar 89 slides frictionally between two longitudinally 50 grooved channel-bars 91-91 which are lined with leather strips 91'-91'. Said channel-bars 91-91 are slotted, as shown at 55 93, to receive the inner ends of the pins 84. As shown in Figs. 24 and 30, the channel bars 91-91 are held frictionally against the friction bar 89 by means of a yoke 92, one end of which is provided with a pin 84' which registers with an opening 92' in one of the bars 91. The opposite end of 60 the member 92 is provided with a plate 93' which carries a screw-threaded stud 94', the inner end of which registers with an opening 96' in the other channel bar 91, the pins 84' and 94' serving to hold the yoke 92 in place. Carried by the stud 94' is a spiral 65 spring 97', one end of which bears against one of the channel bars 91, the opposite end of which bears against a shoulder of the screw-threaded stud 94' serving to maintain a pressure between the channel bars

91-91 and the frictional sliding bar 89. The plates 70 project forward and are placed a proper distance to permit a charge of cigarettes to be received therebetween. The cross-head 71 and its blocks 83 and the horizontal rods 85 carried by the cross-head all move forward in the same relative position as shown in Fig. 16.

It will be understood that the transfer wheel is at rest with a pocket containing a 75 charge of cigarettes directly in line with the cross-head 86 and the plates 70.

The initial movement of the cross-head 71 moves the blocks 83 and their pins 84 to the limit of the slots 93, which slots are 80 substantially the same length as the space between the cross-head 86 and the cigarettes, and during this movement the friction-bar 89 is frictionally held from movement while the longitudinal rods 85 move with respect 85 thereto. This causes the cross-head 86 to move away from the block 87, and by the time the pins 84 reach the ends of the slots 93 the cross-head 86 is moved against the charge of cigarettes, and further movement 90 of the cross-head 71 will now cause all the parts to move together, so that the charge of cigarettes within the plates 70 are projected against the vertically-supported 95 wrapper as disclosed in Fig. 16. With the 100 parts in the position shown in Figs. 1 and 16, the charge of cigarettes and the plates 70 are about to enter the throat of the folding device provided with side rollers 96 and 97. This movement simultaneously 105 folds the wrapper over the cigarettes into a U-shaped form as shown in Fig. 17. As the wrapper assumes the U-shaped position, the portion 95 thereof is tucked in by the rollers 96 and 97. As the wrapper passes into the 110 folding magazine, the flap 125 is moved to a horizontal position by contacting with the bottom of the magazine, and the longitudinal opening left by the walls 98 and 99, the upper flaps of the wrapper enter downwardly inclined slots 99', thus turning the 115 upper flap 100, as shown in Fig. 19, and confining it within the walls 98 and 99. The lower flap 101 still projects horizontally through the lower opening formed by the 120 walls 98 and 99, and it is at this point that the paste is preferably applied to the lower flap in the following manner:—Arranged above the folding mechanism, as best shown in Figs. 10, 11 and 12 is a paste spool 125 consisting of shaft 102 having adjustably secured thereto a pair of paste-disks 103 and 104, of such a diameter as to rub upon the upper surface of the lower flaps 101, 101. Shaft 102 is driven by means of a sprocket-chain 105 and sprockets 106 and 107, the latter being secured to a shaft 108, which in turn is geared to shaft 109 carrying on the outer end thereof the sprocket 109' which is connected by sprocket-chain 110 to a 130

4
sprocket 111 carried by the shaft 54 of the wrapper feed drive as shown in Fig. 1.

As disclosed in Fig. 12, directly above the paste-disks 103—104 is a paste-pot consisting of a pair of rollers 112 and 113, the former mounted upon the shaft 108, and the latter upon the shaft 109 which drives shafts 108. The roller 113 is adapted to contact with the disks 103 and 104 to apply the paste thereto, the paste being received from above these rollers, and an idler roller 114 is suspended by suitable hangers 115 removably secured to the side walls of the paste-pot to contact with rollers 112 and 113.

As the wrapper and its contents move along, the lower flap 101 engages an upwardly-inclined slot 116, by which the lower flap is folded upwardly against the now-folded upper flap 100, and the two are pasted together as described the paste being applied to the flaps 101 by the disks 103 and 104.

As previously stated, the plates 70 and the cross-head 86 of the plunger are moving as one up to this point. When, however, the plunger 90 on the friction-bar 89 strikes against the cushion 82 on the frame 81, said friction-bar with the plates 70 are arrested, while the cross-head 71 and the rod 85 and the cross-head 86 all move forward. This causes the charge now wrapped to be shoved out from between the plates 70 and into the rotary pasting-box 117 shown in Figs. 27, 28 and 29 mounted upon shaft 118 and journaled in suitable bearings 119, the shaft 118 being driven by the mutilated gears 120 and 121 see Figs. 1 and 2, the latter being keyed to the vertical shaft 122, which in turn is geared to the countershaft 12 by means of the gear meshing with a bevel gear on said shaft. This pasting-box 117 receives the package with all but the end flap 125 pasted, and in order to apply paste to the upper part of the wrapper, the top and bottom of the pasting-box 117 is provided with an open slot 126, and the means for applying the paste preferably consists of an arm 127 mounted upon the rock-shaft 128 and carrying at its outer end a paste-roll 129, which by means of the spring 130, is held in contact with the paste-roll 112. This roll 129 is intermittently moved from the roll 112 to a position directly above the inner end of the package now held in the box 117, this movement preferably being accomplished by means of an arm 131 keyed to the outer end of the shaft 128.

Connected to this arm 131 is a vertically-arranged plunger 132 held in a vertical position by means of a suitable guide 133 pivoted as at 134 to the side of the frame of the pasting device. The upper end of the plunger is provided with an abutment 135 carrying a roller 136 adapted to be en-

gaged by a cam 137 carried by the shaft 108, 65 whereby the paste-roller 129 is actuated.

Each time the said box 117 receives a wrapper and its contents, it makes a half turn, and in this movement the forwardly-extending flap 125 will be given a quarter 70 turn by its contact with the bottom of the receptacle in which the box turns. At the end of the half turn of the box 117 another package is inserted into the box by the plunger, and the former package is thereby 75 ejected from the box, and in so doing the flap 125 is folded against the now-lower side of the package. The completed package is now aligned with two endless conveyors 80 preferably consisting of the following construction:—

The numeral 137' indicates two endless belts passing around a set of pulleys 138 rotatably mounted at the extreme outer end of the carrier, and a set of pulleys 139 85 mounted upon the vertically-arranged shafts 140 at the inner end of the conveyor. These shafts are connected together at their lower ends by spur-gears 141 and 142, the latter in turn meshing with a train of gears 143— 90 144—145, the gear 145 being mounted upon the vertical shaft 132 from which the conveyor derives its power. A roller 146 arranged transversely of the conveyor at its inner end is adapted to press against the 95 package and complete the pasting of the ends of the flaps 125 to the package. As a means for further pasting and preventing the package from moving upwardly while passing along the conveyor, I preferably 100 provide a longitudinal strip 147 along the upper side thereof, at the inner end, and a similar longitudinal strip 148 at the outer end thereof, the packages being taken from the machine as they pass from the conveyor. 105

Briefly to recapitulate the operation of the machine, the charge of cigarettes between the partitions 19 are transferred to one of the pockets 32 in the rotary transfer wheel 20 by means of the reciprocating plunger 33, the 110 wheel 20 being intermittently rotated while at the same time compressing the charge of cigarettes by a plunger 40. When the transfer wheel 20 has rotated sufficiently to bring the charge of cigarettes into alignment with the cross-head 86 and plates 70, said parts are actuated to pass through the pocket 32 and push the cigarettes against the wrapper 101, which has been fed downward from the feeder 44, and as the cigarettes are pushed further they pass through the folding device which folds the wrapper around said cigarettes, glue being applied to the side flaps 101 by the disks 103 and 104. The charge as thus wrapped is then transferred 125 into the rotary pasting box 117 where the end flap 125 is folded over and glued to the package by the rotation of the box, the glue

having been applied to the package by the paste-roll 129 through the open slot 126. The cross-head 86 and plates 70 have now reached the end of their movement and are drawn back to receive a new charge of cigarettes, bringing them forward as above described, and upon the new package being pushed into the pasting-box 117, the former one is forced out and into the discharge conveyor which transfers the package from the machine.

From the foregoing, and the accompanying drawings, it will be seen that I have provided an organized machine which will automatically count off the articles to be packaged, press them compactly, feed them into the path of a wrapper which is printed, and wrap and fold the printed wrapper around the articles, and finally paste the wrapper preparatory to being delivered from the machine.

It will be obvious that various changes and modifications may be made in the machine without departure from the spirit of the invention, the scope of which may be determined from the appended claims.

I claim:

1. In a packaging machine, the combination with means for holding articles, of transferring means for moving the articles from said holding means including a reciprocating cross-head, longitudinal bars connected therewith, a plunger connected with the outer ends of said bars, a friction bar movably connected therewith, plates secured to the outer end of said friction bar, and means for limiting the movement of the friction bar relative to the longitudinal bars.

2. In a packaging machine, the combination with means for holding articles, of transferring means for moving the articles from said holding means including a reciprocating cross-head, longitudinal bars connected therewith, a plunger connected with the outer ends of said bars, a friction bar movably connected with said bars, plates secured to the outer end of said friction bar, means for limiting the movement of the friction bar relative to the longitudinal bar, and frictional means bearing against the sides of the friction bar for creating a pressure thereon and controlling the movement of said bar.

3. In a packaging machine, the combination with means for holding articles, of transferring means for moving articles from said holding means including a reciprocating cross-head, longitudinal bars connected therewith, a plunger connected with the outer ends of said bars, a friction bar mounted between the longitudinal bars and movably connected therewith, plates secured to the outer end of the friction bar for receiving the articles, a bumper secured adjacent each end of the friction bar, fixed cushions in the path of the bumpers for limiting the movement of the friction bar, channel bars having frictional means connected therewith for receiving the friction bar, and a yoke for holding said channel bars and frictional means against the friction bar for creating a pressure thereon and controlling the movement of said bar.

4. In a packaging machine, the combination of means for applying glue to a wrapped package including an oscillatory paste roll, a rock shaft for imparting oscillatory motion to said paste roll, a plunger flexibly connected to said rock shaft, an abutment secured to the outer end of said plunger, and extending laterally therefrom, means connected with said abutment and engaging said plunger for adjustably securing the abutment thereon, a roller carried by said abutment, and a cam in position to engage said roller for moving the plunger.

5. In a packaging machine, the combination of means for applying glue to a wrapped package including an oscillatory paste roll, a rock shaft for imparting oscillatory motion to said paste roll, a link fixed on said rock shaft, a plunger pivotally connected with said link, a sleeve for supporting and guiding the plunger, an abutment secured to the plunger adjacent the outer end thereof and extending laterally therefrom, means connected with said abutment and engaging said plunger for adjustably securing the abutment thereon, a roller journaled in the outer end of said abutment, and a cam in position to engage said roller for moving the plunger and rock shaft.

In testimony whereof I hereunto affix my signature.

IGNACIO LÁZAGA.
